UNITED STATES PATENT OFFICE

ANTHONY SCHROEDER, OF CLEVELAND, OHIO, ASSIGNOR OF ONE-HALF TO JAMES MERLE FINNEY, OF CLEVELAND, OHIO; ALBERT Y. BECKWITH, ADMINISTRATOR OF SAID ANTHONY SCHROEDER, DECEASED, ASSIGNOR TO MOLLIE SCHROEDER, OF CLEVELAND, OHIO

MACHINE FOR MAKING CONTAINERS

Original application filed May 20, 1925, Serial No. 31,530. Patent No. 1,635,506. Divided and this application filed July 5, 1927. Serial No. 203,558.

This invention relates to mechanism for heading or seaming heads on the bodies of metal containers, for example, barrels, drums, liquid holders, storage tanks and receptacles for dispensing mechanisms and the process of forming, folding and rolling the seams between the heads and the bodies thereof. The invention may be applied to the manufacture of containers for storing or shipping purposes, sometimes termed steel barrels or drums. It will be obvious that the invention may be used for making such containers or tanks of varying sizes and formed from sheet metal of different gage, as desired. The invention is particularly useful in the manufacture of containers, tanks and receptacles having the seams for their heads disposed around their side walls, so that the heads will be flat instead of being provided with up-standing rims (usually referred to as chimes) around the edges of the heads.

This application is a division of my application filed May 20, 1925, Serial No. 31,530—
see Letters Patent No. 1,635,506.

One object of the invention is to provide an improved seaming mechanism of relatively simple construction and capable of folding and interlocking the flanges of a container body and a head therefor to form a seam in a rapid and ready manner, whereby the amount of labor usually required is reduced and greater output results.

Another object of the invention is to provide an improved mechanism for seaming the flanges of a container body and a head therefor wherein the head is flat and disposed in a plane at one end of the container body.

Another object of the invention is to construct an improved seaming machine wherein provision is made for supporting the head and body with their flanges in concentric relation to each other and the axis about which they rotate during the seaming operation and for insuring this relation while seaming of the flanges is effected.

Another object of the invention is to provide an improved seaming mechanism seaming a head or top on a tank body whereby the appearance of the finished tank is im-

proved and its surface lends itself for decoration purposes, the tank may be readily cleaned and the accumulation of grit, dirt and material is avoided.

Other objects of the invention will be apparent to those skilled in the art to which my invention relates from the following descriptions taken in connection with the accompanying drawings, wherein

Fig. 1 is an elevation of a mechanism embodying my invention.

Fig. 2 is a section on the line 2—2 of Fig. 1.

Fig. 3 is a fragmentary section on the line 3—3 of Fig. 2.

Fig. 4 is a section on the line 4—4 of Fig. 3.

Fig. 4a is a view on the line 4a—4a of Fig. 3, looking in the direction of the arrows.

Fig. 5 is a fragmentary view of a seaming roller, in elevation and the container body and a head therefor in section, embodying my invention; the seaming roller being in its first or starting position.

Fig. 6 is a view similar to Fig. 5, but showing the position of the roller when operated to its second position.

Fig. 7 is a fragmentary view showing the final operation of rolling down the seam.

In the drawings, 1 indicates as an entirety a frame. The frame 1 may comprise a table or bed 2, supported on suitable legs 2a, and a pair of upright members 3 connected at their upper ends by a cross member 4. The members 3 may be spaced to receive between them the largest sized receptacle or tank desired to be made on the machine.

The frame 1 may also be provided with a member 5 extending laterally from one side of the machine.

The elements of the frame, just referred to, may be integrally connected or otherwise formed. At its remote or outer end, the extension member 5 is provided with an upright shaft hanger 6, provided with bearings 7. The bearings 7 and bearings 8 provided on the adjacent end of the table 2, support a shaft 9, the purpose of which will be later set forth.

10 indicates a vertical shaft mounted in suitable bearings provided centrally of the table 2. 11 indicates a gear fixed to the shaft 100

10. The gear 11 is preferably a bevel gear and is driven by a bevel pinion (not shown) on the inner end of the shaft 9. 12 indicates as an entirety the driving means for the shaft 9. The driving means 12 preferably comprises a pulley 12a, loosely mounted on the shaft 9, and clutch elements 13. One clutch element is fixed to the pulley 12a; the other clutch element is splined to the shaft 9 and connected with and released from the first mentioned element by a lever 14, in a well known manner.

15. 15 indicates a base member supported on the table 2. The base member 15 is so shaped and contructed that it encloses the gear 11 and driving pinion therefor. Centrally, the base member 15 is formed with an opening through which the shaft 10 and hub member thereon extends. The base member 20 may be provided with an integral, radially extending bracket 16, the purpose of which will be later set forth.

25. 17 indicates a support connected to the upper end of the shaft 10 and arranged to receive the tank body, indicated at A, and the head, indicated at a, to be seamed thereto. In the present illustrative form of the mechanism, the seaming operations are carried out at the lower end of each body A and the head a seamed thereto preferably becomes the top of the tank or receptacle. The bottom of the receptacle may be secured to the body in any desired manner.

35. 18 indicates the flange of the head a bent upwardly at an inclined angle. 18a indicates the flange of the body bent upwardly at an inclined angle, preferably corresponding to the inclination of the head flange 18 so as to lie in face to face relation therewith. As 40 shown, the head flange 18 has a width greater than the flange 18a (preferably approximately twice its width) so that it may be rolled or bent over the flange 18 in effecting the first seaming operation. In this form of construction, due to the arrangement of the flanges 18, 18a, the body A rests at its end on the head a, when assembled for the seaming operation—see Fig. 5.

50. The support 17 is preferably formed in its upper surface with a recess 17a, the sides of the recess being inclined so as to support the inclined flange 18 of the head a. The support 17 is preferably detachably connected to the shaft 10 so that it may be removed and 55 a support of a different diameter substituted according to the size of the tank to be made at any time. The bottom of the recess may be a plane surface and the head a may be flat and engage with such surface; or such surface may be concaved slightly and the head correspondingly shaped, so that the latter, when the tank is in use, will form a slightly convexed surface, thus insuring the flow of any liquid dropping or accumulating on the head off therefrom over the side edges of

the tank. In the use herein of the terms "flat" or "plane", I intend to comprehend thereby a head which may be slightly curved.

19 indicates a plate adapted to engage the upper end of the body A and hold it and the head a firmly on the support 17. The plate 19 is fixed to the lower end of a rod 19' slidably mounted in guides 20, which are provided on the cross member 4, and bearings 21 provided on a cross piece 22. The cross piece 22 is adjustably connected at its opposite ends to the upright frame members 3.

23 indicates a sleeve fixed to the rod 19', preferably above the cross member 4, having collars 23a which form bearings for the bifurcated end of a lever 24, whereby the latter is pivotally connected to the sleeve. The lever 24 is pivotally supported in any well known manner, preferably in a bracket 24a, on the cross member 4 and counterbalanced at its outer end, as shown at 25. 26 indicates devices for operating the lever 24 about its pivot to raise and lower the rod 19'. The rod is raised to disengage the plate from the body (see dotted lines in Fig. 1) and thus permit the positioning of a tank body and head on the support 17 or their removal therefrom; it is lowered to move the plate 19 into engagement with the body and thus clamp it and the head firmly on the support 17 and hold them thereon during the rotation of the support 17 and the forming of the seam. The devices 26 preferably comprise a pair of

links 27, 27a, connected at their remote ends to the lever 24 and a rock shaft 28, respectively. The rock shaft 28 is connected through an arm 28a to a rod 29, which is operated by means 30, such as a compressed air operated piston, controlled by a lever 30a. The operating means 30 may comprise a cylinder 30b containing a piston, a valve mechanism to admit air to either side of the piston, a rod 30c connected to the piston and a bell crank 30d mounted on the cross member 4 and connected to the rod 29. The compressed air operated piston not only serves to move the clamping plate 19 into engagement with the drum A, but by maintaining the air pressure on the piston, it may be utilized to effect a yielding engagement of the plate 19 with the tank body A while the seaming operation between it and a head a on the support 17 takes place for a purpose which will later appear.

100. The cross piece 22 is preferably so connected to the frame members 3 that it can be adjusted to different positions according to the size of the drum or tank to be formed. As these supporting and adjusting devices form no part of my present invention, a detail description thereof will not be necessary.

105. 31 indicates as an entirety the mechanism for folding or bending the flange 18a of the container body A and the flange 18 of a head a into interlocking relation ready for a roll-

ing down operation to compress the sections of the folded flanges into close face to face relation to complete the seam and thus permanently secure the head and body together 5 in a liquid tight manner. The folding or bending mechanism 31 is constructed to provide for movement of the seaming device through a plane disposed substantially radially of the body A in a lateral or downward 10 direction relative to the body end. This movement may be in a rectilinear direction, but to simplify the construction and the means for guiding and effecting this movement of the seaming device, the seaming device 15 vice is mounted on one end of a relatively long arm that is pivoted at its opposite end, so that the seaming device traverses a relatively long arc as the bending operation is effected. Of this folding or bending mechanism, 20 32 indicates a base secured in any desired manner to the bracket 16. At its outer end, the base 32 is provided with an up-standing lug 33 in which is formed a screw threaded opening 33a, adapted to receive a feed screw 34; the lug 33 thereby serving as a 25 nut for the screw 34. At its outer end the feed screw 34 has fixed to it a relatively large wheel 35, by means of which the screw 34 may be rotated in either direction. At its 30 inner end the screw 34 is reduced to form a shaft 34a rotatably fitting an opening 36 in a slide or carriage 37. The slide 37 may comprise a shoe 37a slidably fitting ways 32a formed in the base 32 and held therein by 35 overhanging strips 38, and a vertically disposed web 37b having a flange 37c. The ways 32a are parallel to an imaginary line preferably extending radially of the axis of the container body A. As shown in Figs. 1, 40 3 and 4, the rear or outer end of the shoe 37a is provided with an up-standing lug 37a' in which the opening 36 is formed. The shaft 34a is provided on its inner end with a collar or nut 39 which bears against the inner face 45 of the lug 37a'. Due to the engagement of the collar 39 and the shoulder resulting by reducing the end of the screw 34 with the lug 37a', the shaft 34a is connected to the slide 37 so that when the screw 34 moves endwise in 50 either direction, due to its rotation, it carries the slide 37 with it, the purpose of this operation being to permit of adjustment of the seaming device into proper position to engage the flanges 18, 18a. The inward adjustment of the slide is limited by a stop 31', which may be adjusted so as to keep the seaming device from engaging the body A. The stop 31' may comprise a lateral extension on 55 one of the strips 38 having a threaded opening for a bolt 31a, the free end of which is disposed in the path of movement of the lug 37a' and is engaged thereby when the shoe is operated toward the body A. The bolt 31a is rotated to adjust its free end so as to limit the adjustment of the shoe. 40 indicates an 60 arm pivotally connected at one end to the slide 37, preferably upon the web 37b thereof, and adapted to swing upwardly and downwardly thereon. The arm may comprise a base portion 40a, having a flat face slidably engaging the inner face of the web 70 37b and guided thereby, and spaced bearing blocks or lugs 40b formed with aligned openings to rotatably support a shaft or spindle 41, carrying at its outer end a seaming device 42 to which reference will later be made. 75 The pivot connection for the arm 40 preferably comprises a bolt 40' extending through openings formed in the web 37b and arm 40, the bolt being held in position by a suitable nut 40''. The arm 40 may be and preferably 80 is held against lateral movement away from the web 37b by a plate 43 extending from the shoe 37a to the flange 37c and suitably secured thereto—see Figs. 3 and 4a. As shown in Fig. 4a, both side faces of the outer bearing block 40b are flat and such block has a width adapting it to fit between the web 37b and plate 43, so as to be guided between them vertically about the pivot 40'. The spindle 85 41 is held against endwise movement in the bearing blocks 40b by the hub of the seaming device 42 engaging one end of the inner block 40b and a collar 44 engaging the opposite end thereof. 45 indicates devices for adjustably supporting the arm 40 in what may be termed its normal position. 49 preferably comprise a screw 50 extending through and engaging screw threads provided in an opening 51 formed in the flange 37c, the opening 51 being preferably arranged to support the screw 50 at substantially right angles to the arm 40. At its outer end, the screw 50 carries a hand wheel 52, by means of which it may be rotated, which operation will move the end of the screw downwardly and thus act through the arm 40 to move the seaming device 42 from the position shown in Fig. 5 to the position shown in Fig. 6, thereby bending or rolling the flange section 18 and body flange 18a into close relation, and completing one step 10 of my process in forming a container. As will be understood from the foregoing description, the arm 40 is mounted to swing on a horizontal axis, and being disposed in a plane that is radial of the axis of the body 20 A, its movement downwardly, due to operation of the screw 50, will be in this plane. 53 indicates a stop for limiting the downward movement of the arm 40 to prevent undue pressure on the flanges by operation of the seaming device to a point beyond that required to carry out this step of seaming the flanges 18, 18a, into folded relation. The stop 53 is preferably mounted on the screw 30 50, in which arrangement it may comprise one or more nuts 54, thereby providing a simple form of adjustment for the stop to regulate the throw or movement of the arm 40 and through it the seaming device 42.

35 The mounting of the seaming device herein shown is preferable on account of its simplicity and the seaming operation may be readily carried out because the seaming device 42 swings on a relatively long radius, 40 so that its arc of movement approximates a straight line. In this form of construction, the active face of the seaming device 42 is formed with a groove 42x shaped to cause the edge of the flange 18, as the device moves 45 downwardly, to bend laterally and roll over on itself with the flange 18a interlocked underneath the rolled over portion, as shown in Fig. 6. In seaming the head a and body A according to this process, the head and 50 body are respectively provided with the flanges 18, 18a, and then assembled on a rotatable support; next, the flange 18 is rolled or bent over on the flange 18a to perform the first seaming operation. This step of the 55 process is effected by the movement downwardly of the seaming device 42 from the position shown in Fig. 5 to the position shown in Fig. 6.

60 Next, I roll the interlocked flanges down against the side wall of the body A. In performing this step, I prefer to remove the body A and head a from the support 17 and position it on a rotating member having a mandrel fitting against the inner side wall 65 of the body A and applying under pressure

a suitable roller to the folded flanges to roll them against the outer side wall of the body. This step may be termed the final seaming operation and may be carried out on a machine shown for illustrative purposes in Figure 7, where a portion of the mandrel 68 is shown on the inner side of the container body A and the rolling down roller 69 is engaging the seamed portions of the flanges to roll them down into their final or face to face position. Where it is desired to make the seam flush with the body side wall, the latter is formed with an annular recess to receive the related flanges. It will thus be seen that in this process, the seam may be disposed exteriorly of the body side wall or countersunk to lie flush therewith.

70 It will be noted from Fig. 6 that the metal of the flanges 18, 18a, at the end of the first seaming operation is in a curved condition, resulting from the method of carrying out this step; however, in carrying out the next step (see Fig. 7), the sections of the flanges are rolled flat in face to face relation, thus 75 forming a liquid tight seam or joint.

80 In the herein disclosed process or method, I prefer to bend the free edge of the flange 18 inwardly slightly, as shown at 18c, the purpose of which is to facilitate the rolling operation, by making it easier for the seaming device 42 to start the metal in its rolling movement.

85 The joint or seam resulting from the process is liquid and gas tight, so that the container may be used for storing or shipping any kind of materials.

90 In my improved construction I seam the head to the side wall of a tank body in a ready and easy manner without danger of spreading the flanges or the sections thereof, thus insuring positive operations of the seaming device.

95 In the foregoing description I have used the term "upwardly" in connection with the flanges for the head and body for convenience since the illustrated form of mechanism shows the head supported horizontally and the body disposed vertically thereon; but in such use no limitation is to be imposed on the scope of the invention since it will be 100 understood that these elements may be arranged with the head in vertical position and the body disposed horizontally and the seaming effected while they are in these positions; or these elements may be reversed, that is, the head a positioned on the upper 105 end of the body A and the seaming device disposed to effect the seaming operation upwardly.

110 In the product formed by my improved mechanism the tank has a neat and smooth outline or appearance, the seam being substantially countersunk into the side wall of the tank, the top being flat and the peripheral edge being flangeless or chimeless; thereby 115 120 125 130

- eliminating a ring or obstruction around the edge of the top to collect dirt, grit and liquid, and providing a surface which may readily be cleaned. This form of construction adapts the tank most advantageously for use as part
- 5 of a dispensing mechanism for liquids and oil and similar materials. Where the tank is used to store gasoline, oil, grease or other lubricant and has associated with it a dispensing means therefor, accumulation of such material on top of the tank, as well as grit and dirt, is avoided. By reason of the smooth exterior surface of the tank and the planular shape of its top, it may be readily cleaned and polished.
- 10 15 To those skilled in the art to which my invention relates, many changes in construction and widely differing embodiments and applications of the invention will suggest themselves without departing from the spirit and scope thereof. My disclosures and the description herein are purely illustrative and are not intended to be in any sense limiting.

What I claim is:

- 20 25 In a seaming apparatus for joining a head having an upwardly inclined flange and a body having an inclined flange of less width than said flange and seated within and in face to face relation with the latter, the combination of a plane support arranged to engage with and support the head and body, means for rotating said support, a seaming device, and means for moving said device substantially in an inclined inwardly direction in the plane of said flanges to curl the head flange over said body flange.
- 30 35

In testimony whereof, I have hereunto subscribed my name.

ANTHONY SCHROEDER.
